United States Patent Office

Des. 191,270
Patented Sept. 5, 1961

191,270

TROPHY

Norbert Serbin, 3527 N. Oconto St., Chicago, Ill.

Filed Mar. 21, 1961, Ser. No. 64,427

Term of patent 14 years

(Cl. D29—23)

FIG. 1

FIG. 2 is a three-quarters rear perspective view taken from the side not seen in FIG. 1.

The fragmentary broken line showing of the electric cord is for illustrative purposes only.

I claim:

The ornamental design for a trophy, as shown and described.
